(57) **CLAIM**

The ornamental design for the portable liquid filter with adjustable legs, as shown and described.

DESCRIPTION

FIG. 1 is a top front perspective view of my portable liquid filter with adjustable legs;

FIG. 2 is a top elevational view of my design;

FIG. 3 is a bottom elevational view of my design;

FIG. 4 is a front elevational view of my design;

FIG. 5 is a rear elevational view of my design;

FIG. 6 is a bottom rear perspective view of my design;

FIG. 7 is a top rear perspective view of my design;

FIG. 8 is a top front perspective view of my design, illustrating a condition of use;

FIG. 9 is a bottom front perspective view of my design illustrating a condition of use; and,

FIG. 10 is a right side elevational view of my design, illustrating a condition of use.

In the drawings, the broken lines depict unclaimed subject matter only and form no part of the claimed design.
